Inventor:
Clyde H. Faris
Clinton C. Sisson
Attorney.

UNITED STATES PATENT OFFICE.

CLYDE H. FARIS, OF ROANOKE, VIRGINIA.

MEANS FOR ATTACHING CAR-WALL LININGS.

Application filed October 8, 1924. Serial No. 742,410.

To all whom it may concern:

Be it known that I, CLYDE H. FARIS, residing at Roanoke, county of Roanoke, State of Virginia, and being a citizen of the 5 United States, have invented certain new and useful Improvements in Means for Attaching Car-Wall Linings, of which the following is a full, clear, and exact description, such as will enable others skilled in 10 the art to which it appertains to make and to use the same, reference being had to the accompanying drawings, which illustrate the preferred form of the invention, though it is to be understood that the invention is 15 not limited to the exact details of construction shown and described, as it is obvious that various modifications thereof within the scope of the claims will occur to persons skilled in the art.

20 It is necessary to line metallic walls of railway cars with a wooden lining so that the car may be used to transport any kind of lading. The lining prevents the moisture, due to condensation on the inside of the 25 metallic plate, from coming in contact with the grain lading and causing mildew, or if the car is loaded with cement, this moisture would cause hardening of portions of the cement requiring resacking. There are also 30 limitations regarding the loading of explosives prescribed by the Interstate Commerce Commission. A wooden lining is also useful to block the lading to.

35 Wooden nailing strips are convenient because the lining may be secured thereto by ordinary nails, which are easily applied and easily removed. Such nailing strip, however, must be secured to the end wall without any loose means (such as a bolt) extending 40 from the outside to the inside of the wall as moisture would get into the car. Even if such means were made solid (such as a rivet) frost would follow through and afterwards melt. In my arrangement I secure 45 the lining to the nailing strip by entirely separate means from that which secures the nailing strip to the wall.

50 End walls for railway cars are in service which are made of a metallic plate with a plurality of corrugations formed therein. In such a construction my holder fits with-

in such corrugation, thus obtaining a very neat, compact and tight arrangement.

In the drawings:

Fig. 1 shows a section of a corrugated 55 end wall for a railway car with my invention applied thereto.

Fig. 2 shows a front elevation of the holder and pin.

Fig. 3 shows a top plan view of the holder 60 and pin.

The holder 1 is secured to the wall 2 of the car by rivets 3 or any other convenient means. The holder may be made of upper and lower separate pieces but the one piece 65 holder with integral upper and lower members, as illustrated, is preferable. The upper member 4 is provided with a flange 5 projecting upwardly from its outer edge and this upper member and its flange are provided with slot 6. The lower member 7 is provided with perforation 8. The nailing strip 9 for the lining 10 is positioned between the members of the holder and is provided with a groove 11 in its outer surface 75 which registers with the slot 6 of the upper member 4 and the perforation 8 of the lower member 7. The headed pin 12 is inserted in the groove 11 and perforation 8, as shown by dotted lines in Fig. 1, and the 80 head 13 is then inserted in the slot 6 and dropped behind the flange 5. A cotter key 14, nut or any other convenient means is then applied to the lower end of the pin to retain its head behind the flange which 85 thereby retains the pin and the nailing strip in place. The lining 10 is then nailed to nailing strip 9.

The nailing strip may be positioned either 90 horizontally or vertically.

I claim:

1. In combination with a wall for a railway car, a holder secured to said wall, comprising an upper member provided with a slot and a flange, a lower member provided with a perforation, a nailing strip positioned between said members and provided with a groove, a lining secured to said strip, a headed pin engaging said slot, perforation and groove with its head behind said flange, and means to retain said head in position behind said flange. 100

2. The combination of a metallic wall for a railway car having a corrugation formed therein, a holder fitting within said corrugation and secured to said wall, said holder comprising an upper member provided with a slot and a flange, a lower member provided with a perforation, a nailing strip po-

sitioned between said members and provided with a groove, a lining secured to said strip, a headed pin engaging said slot, perforation and groove with its head behind said flange, and means to retain said head in position behind said flange.

10

CLYDE H. FARIS.
